Edwin Leonard Lane, Kingston-on-Thames, England

Application June 27, 1957, Serial No. 668,464

3 Claims. (Cl. 103—37)

The object of the invention is the provision of an improved constructional arrangement of variable delivery hydraulic pump, of the type having a plurality of cylinders arranged in communicating pairs, whereby it is possible to obtain a high operating output pressure and high volumetric efficiency, an output delivery infinitely variable between zero and full capacity, and certain other valuable advantages which will be apparent from the following description.

According to the invention a variable delivery hydraulic pump of the type specified is characterised by an arrangement whereby the pistons of each communicating pair of cylinders are respectively driven from a common shaft through the media of eccentrics the sheaves whereof are mounted on the shaft and connected thereto by helical splines of opposite hand, such that an axial adjustment of the shaft produces a relative angular displacement of the eccentrics and consequently a variation of the volumetric output.

One embodiment of the invention, and certain minor modifications thereof, are illustrated in and are herein-after described with reference to the accompanying diagrammatic drawings. In said drawings, Fig. 1 is a longitudinal section of the pump, Figs. 2 and 3 are respectively sections of the lines II—II and III—III of Fig. 1, Fig. 4 is a section on the line IV—IV of Fig. 3, Fig. 5 is a fragmentary elevation of alternative manual means for effecting an axial adjustment of the driving shaft, and Fig. 6 is a section on the line VI—VI of Fig. 5. Fig. 7 illustrates apparatus for controlling the pump by hydraulic servo mechanism, and Fig. 8 illustrates further alternative control means, depending in this case upon output pressure.

The pump depicted in Figs. 1 to 4 comprises a block 10 housing five equiangularly spaced connected pairs of cylinders 11, 12, each pair being sealed by individual pistons 13, 14 and furnished with a single inlet valve 15 and a single outlet valve 16, both said valves being of the seated type. The output valves 16 communicate by means of an annular duct 161 with the pump delivery outlet 162. The cylinders are disposed radially about an axially mounted driving shaft 17 which may be coupled at 171 to an electric motor or other prime mover (not shown), and having splined thereon two eccentrics 18, 19 which are respectively located opposite the inner ends of the pistons 13, 14, which latter are arranged to bear against grooved reaction rings 20, 21 mounted on the eccentric sheaves by needle bearings 22, 22, the arrangement being such that the pistons are reciprocated in their cylinders by the throw of the eccentrics. Each eccentric is preferably made as an extension of a tubular shaft 23, supported by a pair of taper roller anti-friction bearings 24, 24.

The splines 25, 25 whereby the eccentrics 18, 19 receive rotary motion from the driving shaft 17 at equal speeds are helical and of respectively opposite hand, and the arrangement is such that the effect of imparting an axial movement to the driving shaft 17 is to produce a rotary movement of the eccentric 18 relative to the other 19; provision is made for an axial shaft adjustment sufficient to move each eccentric through an angle

2

of 90°, so that the conditions may be varied from a relative disposition of the eccentrics of 180°, in which the stroke of the pistons 13 exactly balances that of the pistons 14 and the output delivery has a zero value, to an eccentric setting in which the pressure stroke of the pistons 13 and 14 coincides and the output delivery is accordingly at a maximum. Any relative setting of the eccentrics between these limits will provide a proportional delivery rate.

10 The inlet may be connected to a reservoir so that suction lift can be obtained, and in such an arrangement return springs will be required to maintain the pistons 13, 14 in operative contact with the eccentrics 18, 19. Such an arrangement may however be disadvantageous and 15 it is considered preferable to supply hydraulic fluid to the inlet valve 15 by the gear-type constant delivery feed pump illustrated at the right-hand end of Fig. 1, and in Fig. 3, which comprises a gear 26 fixed on the shaft 171, a gear 27 meshing with the gear 26 and 20 arranged to pump liquid entering the gear chamber 28 at 29 through the duct 30 by the passage 31 into the annular header duct 32, whence the liquid has access to the inlet valves 15. By these means the use of return springs for the pistons is rendered unnecessary, whilst 25 cavitation and starvation of flow to the variable delivery pump are avoided and the resultant high volumetric efficiency prolongs the working life of the valves. The inlet pressure may be maintained by employing a feed pump having a volumetric output greater than the maximum flow through the variable delivery pump, and passing the surplus feed to exhaust at 33 (Fig. 3). Conveniently, 30 the inlet header 32 may be provided with a relief valve of the balanced type offering a constant hydraulic resistance at varying rates of flow, such resistance being 35 determined by external means of adjustment. By this arrangement a back pressure is maintained in the inlet header 32.

In case the driving shaft 17, being relatively unstable, 40 should tend to amplify undesirable vibration forces due to excessive working clearances in the transmission elements (caused e. g. by wear or inaccuracies in manufacture), it may be desirable to attach to the end of a cylindrical extension 34 of said shaft 17 the piston-rod 35 and piston 36 of an oil-filled double-acting dash-pot 37. 45 A supply of oil is led from the header 32 through the passage 38 and a pipe 39 to either side of the dash-pot piston 36, and the dash-pot cylinder is maintained filled with oil by check-valves 40, 41 when the pump is at rest, the piston 36 being in hydraulic balance and air being 50 excluded notwithstanding possible oil-leakage.

When the axial position of the shaft 17 is such as to provide a given output delivery, the centripetal forces acting through each eccentric 18, 19 react axially within the shaft, which is therefore substantially in equilibrium. 55 Any out-of-balance force tending to displace the shaft axially must overcome the resistance in either direction of spring-biassed valves 42, 43 of small orifice which are provided in the dash-pot piston 36. Thus, each such valve 42, 43 will subject the oil in the dash-pot to a unit pressure which, multiplied by the annular area around the piston-rod 35, will resist axial movement of the shaft 17.

The shaft 17 is operated for control purposes by means of a lever 44 arranged to rotate a pinion 45 meshing with a rack 46 on the shaft-extension 34 and acting through 60 thrust-bearings 47, 48. Such form of control means has a high mechanical advantage capable of overcoming the resistance of the dashpot valves 42, 43 and thereby enables control to be effected manually without undue effort.

65 An alternative device for operating the helical shaft 17 for control purposes is shown in Figs. 5 and 6. In this case a gear quadrant 49 secured to an extension of the

pinion 45 is rotated by a worm 50 and handwheel 51. Stops may be fitted to bear against the quadrant 49 and limit its movement. With this arrangement the dashpot assembly 35, 36, 37 may be dispensed with.

Which ever of the aforescribed means for axial adjustment of the shaft 17 is employed, the effect of such adjustment is to alter the phase relationship of the eccentrics 18, 19 and therefore of the pistons 13, 14, with the result that the volumetric output of the pump is regulated accordingly.

The radial pumping action of the pistons 13, 14 at high pressure, and the consequent reaction of the liquid upon the helical splines 25, 25, are resisted by the combined axial and journal anti-friction bearings 24, 24. This arrangement enables advantage to be taken of the centrifugal pumping characteristics of taper roller bearings which are used in this situation, as illustrated in Fig. 1. A small volume of the surplus oil from the feed pump is tapped from the header 32 and metered through the passages 52 controlled by the needle-valve 53 (Fig. 4) to the chamber 54 containing the bearings 24 and eccentrics 18, 19. Said passages 52 feed oil between the taper roller bearings 24 which circulate oil to the innermost bearing 55 of the feed pump, the thrust bearings 47, 48, and most important, to the eccentrics 18, 19 and their needle-roller supported reaction rings 20, 21. This flow is drained to exhaust through passages 56, 56 in which are provided light check-valves 57, 57 which keep the pressure in the transmission chamber 54 slightly above atmosphere to exclude air and ensure the regular replacement of oil, thus maintaining its lubricity.

It is a particular advantage of the present pump construction that it lends itself, due to the rectilinear characteristics of the control element and to the fact that the helically-splined shaft 17 is maintained in equilibrium whilst transmitting considerable power, to remote control by suitable pneumatic, electric, hydraulic and mechanical media, without locking the element. Thus, in the embodiment illustrated in Fig. 7, there is a manually-operable control valve 58 arranged to feed surplus oil fed from the header 32 via the pipe 59 to a double-acting hydraulic ram 60 which is axially attached to a rack member 61 meshing with a quadrant 62 operably associated with the pinion 45 by which the rack 46 on the extension 34 of the driving shaft 17 is adjusted. As will be evident from Fig. 1, the position of the control valve 58 will be effective to select the direction of movement of the ram 60 and therefore the direction of adjustment of the shaft 17.

Fig. 8 illustrates means by which the rate of delivery of the pump may be controlled. The pinion 45 is connected to a quadrant 63 which meshes with a slidably mounted rod 64 which latter is biassed to a position corresponding to preset or full delivery by a spring 65 compressed between the housing 66 and a collar 67 on said rod 64. On increase of output pressure in the delivery outlet 162, such pressure is made to act, through the pipe 68 upon a single-acting ram constituted by the end of the dashpot piston rod 35 (or its equivalent), in opposition to the force exerted by the spring 65, and on overcoming the latter, to move the shaft 17 to a position of zero, or reduced, delivery. A useful feature of this control arrangement is that should oil escape from the pressurised system during such high-pressure period, the resulting drop in delivery pressure will cause the spring-biassed driving shaft 17 to move and enable the pump to make up losses and restore the desired pressure. The position of the rod 64 may be preset by adjusting the knurled nuts 69, 69 on the screw-threaded extension 70 of said rod.

What I claim as my invention and desire to secure by Letters Patent is:

1. A variable delivery hydraulic pump comprising a plurality of cylinders arranged in communicating pairs, means for supplying liquid to each pair of cylinders, an exhaust valve for each pair of cylinders, a driving-shaft,

a piston in each cylinder, there being on said driving-shaft in respect of each pair of cylinders two eccentric sheaves each in helically splined relationship with the shaft, each piston being arranged to bear against the periphery of one such sheave, means for shifting said shaft axially in relation to the sheaves for producing relative rotation thereof, and means for damping axial displacement of said shaft in both directions, said damping means including a dash-pot, a double-acting piston in said dash-pot and attached to said shaft for axial movement therewith, a port at each end of the dash-pot, means supplying low pressure liquid to said ports, two ducts through the piston for connecting the compartments of the dash-pot on opposite sides of the piston, and in each such duct a single-acting self-seating valve for restricting flow of fluid through the duct, said valves being arranged to operate in opposite direction.

2. A variable delivery hydraulic pump comprising a plurality of pumping units, each said unit including two inter-communicating cylinders, a driving-shaft, said units being equiangularly assembled about said driving-shaft radially thereof, a header, means for supplying liquid to said header, inlet-valves respectively connecting the header with said units, an exhaust valve in each unit, a piston in each cylinder, there being on said driving-shaft in respect of each assembly of units two eccentric sheaves each in helically splined relationship with the shaft, each piston being arranged to bear against the periphery of one such sheave, means for shifting said shaft axially in relation to the sheaves for producing relative rotation thereof, and dash-pot means for damping axial displacement of said shaft in both directions, said damping means including a dash-pot, a double-acting piston in said dash-pot and attached to said shaft for axial movement therewith, a port at each end of the dash-pot, means supplying low pressure fluid to said ports, two ducts through the piston for connecting the compartments of the dash-pots on opposite sides of the piston, in each such duct a single-acting self-seating valve for restricting flow of fluid through the duct, said valves being arranged to operate in opposite directions.

3. A variable delivery hydraulic pump comprising a plurality of cylinders arranged in communicating pairs, means for supplying liquid to each pair of cylinders, an exhaust valve for each pair of cylinders, a driving-shaft, a piston in each cylinder, there being on said driving-shaft in respect of each pair of cylinders two eccentric sheaves each in helically splined relationship with the shaft, each piston being arranged to bear against the periphery of one such sheave, taper roller bearings supporting said shaft, means supplying lubricant fluid to said bearings, the arrangement of said bearings being such that said lubricant is delivered thereby to working parts of the pump, means for shifting said shaft axially in relation to the sheaves for producing relative rotation thereof, and means for damping axial displacement of said shaft in both directions, said damping means including a dash-pot, a double-acting piston in said dash-pot and attached to said shaft for axial movement therewith, a port at each end of the dash-pot, means supplying low pressure liquid to said ports, two ducts through the piston for connecting the compartments of the dash-pot on opposite sides of the piston, and in each such duct a single-acting self-seating valve for restricting flow of fluid through the duct, said valves being arranged to operate in opposite direction.
